(57) **CLAIM**

The ornamental design for an emblem, as shown and described.

DESCRIPTION

FIG. 1 is a front, left perspective view of an emblem showing the new design;

FIG. 2 is a front elevation view thereof as the emblem may be positioned on a gauge;

FIG. 3 is a front elevation view thereof;

FIG. 4 is a top plan view thereof;

FIG. 5 is a right side elevation view thereof;

FIG. 6 is a left side elevation view thereof;

FIG. 7 is a bottom plan view thereof.

FIG. 8 is a front, left perspective view of an emblem showing a second embodiment of the design;

FIG. 9 is a front elevation view thereof as the emblem may be positioned on a gauge;

FIG. 10 is a front elevation view thereof;

FIG. 11 is a top plan view thereof;

FIG. 12 is a right side elevation view thereof;

FIG. 13 is a left side elevation view thereof; and,

FIG. 14 is a bottom plan view thereof.

The broken lines in FIGS. 2 and 9 showing environmental matter are merely for the purpose of illustrating an example of environment in which this design may be used and forms no part of the claimed design; the dashed lines interior to the emblem in FIGS. 8-10 are for illustrative purposes only and form no part of the claimed design.
